TRICKLE IRRIGATION UNIT

William J. Wichman and Richard A. Vander Ploeg,
Glendora, Calif., assignors to Rain Bird Sprinkler Mfg.
Corp., Glendora, Calif.

Filed Apr. 23, 1975, Ser. No. 570,588

Term of patent 14 years

Int. Cl. D23—01

U.S. Cl. D23—6

FIG. 1 is a front perspective view of a trickle irrigation unit embodying my new design;

FIG. 2 is a side elevational view thereof;

FIG. 3 is a top plan view thereof; and

FIG. 4 is a bottom plan view thereof.

I claim:

The ornamental design for a trickle irrigation unit, substantially as shown.
